(57) **CLAIM**

I claim the ornamental design for barrier mounting bracket for roadway sign base, as shown and described.

DESCRIPTION

FIG. 1 is a perspective view of my invention showing mainly top, front and left end features thereof;

FIG. 2 is a front view thereof;

FIG. 3 is a left end view thereof;

FIG. 4 is a right end view thereof;

FIG. 5 is a top view thereof;

FIG. 6 is a bottom view thereof;

FIG. 7 is a perspective view like FIG. 1 thereof, with the addition thereto of a minor short tubular connector element, it being understood that the bracket of FIG. 7 is identical in all respects to the bracket shown in FIGS. 1-6 except for the addition thereto of the short tubular connector element thereto; and,

FIG. 8 is a right side view showing how brackets of the present invention may be used to mount a roadway safety sign base atop a concrete barrier of the type used to temporarily segregate lanes of roadway traffic.

The broken lines shown in the drawings depicting components such as bracket clamping adjustment fasteners, a conventional concrete barrier used on roadways, portions of a roadway safety sign base, and an extra barrier mounting bracket for roadway sign base shown in FIG. 8 represent unclaimed subject matter and form no part of the claimed design.

1 Claim, 5 Drawing Sheets
